UNITED STATES PATENT OFFICE

GUY F. KOTREBATY, OF NEW YORK, N. Y.

FLOOR AND CEILING MEMBER FOR METAL CONCRETE CONSTRUCTION

Original application filed July 27, 1928, Serial No. 295,705. Divided and this application filed June 3, 1929. Serial No. 367,929.

This invention relates to the construction or sheet steel members adapted for use in building construction and more particularly to an improved design of such members designed for the erection and construction of all kinds of houses and buildings and especially for combined ceiling and floor supports.

This application is a division of my application, Serial No. 295,705, filed July 27, 1928, for Building construction.

It is an object of this invention to provide an expanded steel construction unit provided with stiffening ribs and integral keyways and the invention also comprehends a novel design of key members to cooperate with the keyways.

Yet another object of this invention is the provision of such construction units provided with improved keyways and key members, the whole being so constructed and arranged as to give at one and the same time a substantial and safe construction of relatively light weight which is particularly useful in constructing buildings of any height, and which units are easily handled.

A further object of this invention is the provision of a building material which is cheap in cost, requires relatively unskilled labor for assembling the units into a finished structure, thereby permitting marked economies in building construction.

These and other desirable objects of the present invention will be set forth and described in the accompanying specification and illustrated in the drawings, it being understood, that the examples shown are given merely by way of example, for since the underlying principles may be incorporated in other specific structures it is not intended to limit the constructions to the forms shown except as such limitations are clearly imposed by the appended claims.

In the drawings like numerals refer to similar parts throughout the several views of which

Fig. 1 is a view, partly in section and partly in elevation, of a plurality of construction members assembled and keyed together to form wall and floor sections, a coating of

plastic material being applied to the members to form the surface finish;

Fig. 2 is a vertical section through a floor member;

Fig. 3 is a fragmentary vertical section partly in elevation of a floor member as shown in Fig. 2 showing the slotted ribs and longitudinal stiffening members;

Fig. 4 is a detail vertical section showing the method of uniting a plurality of floor members;

Fig. 5 is a vertical section of a modification of structure shown in Fig. 4;

Figs. 6 and 7 are detailed vertical sections of key members used in conjunction with the floor members;

Figs. 8 to 11 are modifications of the structure shown in Figs. 3 to 5.

Referring now to Fig. 1 there is shown a detail of portion of a completed building showing the relation of the wall members and supports to the combination ceiling and floor members and to the walls of the upper floors.

The construction shown includes a support 81, in which is embedded a channel retaining member 80 provided with fluted tongues 82. Fitted into the channel is a wall member 60, which in turn is capped by a member 83, provided with a channel portion, 84, to receive the top of member 60, the outer surfaces 85 and 86, being expanded or perforated to receive any desired finish.

Member 85 is backed by an integral, unexpanded metal skirt 85a adapted to contact with the solid plastic mass 83a, and to prevent moisture from reaching the mass by conduction or capillary action from the outside stucco coat on member 85. This construction renders the joints of the building substantially water-proof, which feature is also found in the pre-cast slabs shown in my application above referred to, where the grid sections are joined by securing means already described, the solid unexpanded portions preventing the transfer of moisture from one face to the other due to their impermeability.

Superposed upon the members 83, are floor members 90, upon which, in turn, further pedestals or supports 80 may be placed.

The flooring 100a for the completed struc-

tures is built over a flooring member as shown in Fig. 2. This member comprises a bottom expanded or perforated grid portion 100 adapted to serve as a ceiling, integral end portions 101 provided with reentrant cylindrical portions 102, adapted to serve as keyways for the key members disclosed in Figs. 4 and 5. The member shown in Figs. 2 and 3 is provided further with an integral arch portion 10 comprising horizontal slotted rib portions 103, and longitudinal stiffening members 104, traversing the members 103, at right angles as shown. The ends of the sheet metal structure are joined at the crown in any suitable manner as shown at 105. It will thus be seen that a flooring member has been provided which is so designed as to have a maximum compression resistance together with an under surface adapted to receive a finishing coating of stucco or plaster. These members are adapted to be juxtaposed in any desired number and locked together as shown in Figs. 4, 5, 9 and 11 by the key members previously disclosed. These key members comprise a plurality of opposed sections preferably cylindrical having intermediate web portions, preferably one at least of said cylindrical sections being slotted longitudinally to permit of gripping engagement with the respective keyways of the combination floor and ceiling members. When the members are properly assembled, concrete or other monolithic structural material is cast over them to a suitable depth, the result being a monolithic structure having a maximum of strength, yet comprising a minimum of a metallic support together with a minimum amount of the concrete or other material.

In Figs. 6 and 7 are shown cores adapted to join the flooring members by serving as keys which can be filled with concrete or other structural material and thereby made integral with the floor in general, thus permitting the use of deeper concrete beam sections, providing added strength for heavier floor loads.

In Figs. 8-9 and 10-11 there are shown various modifications of the flooring support. The member shown in Fig. 8 is provided with reentrant arcuate portions 104a surrounding the keyways. This construction permits the more perfect arching of the structure adapting it to a heavier floor construction system by shortening the arch span and increasing the concrete beam section width as well as introducing a greater amount of steel for reinforcing purposes. In addition it is to be noted that the combination of the abutting keyways of this modification introduces an additional arch in the bottom portion of the beam section, thus providing additional structural strength.

For bridge flooring or other heavy live load requirements, the structure shown in Figs. 10 and 11 is comparable to that just de-

scribed. The characteristic feature of this construction is the combination of a centrally supported arch, locked by the key system already described, with an integral, keystone-shaped beam section. This results in a deeper beam section, as the bottom of the beam 108 is positioned substantially adjacent to the ceiling grid 100. The keyways are formed as reentrant portions of the vertical stiffening members 112.

The construction units herein described are readily formed from sheet metal of any suitable gauge and can be rolled or otherwise fabricated with a minimum of trouble and expense. In assembling, the units can be put together by unskilled labor, the parts being so formed and so constituted as to preclude any misplacement of the several units. The only skilled labor required in constructing a house, garage or other structure is that of the plasterer for applying the finish coating of stucco or other material to the grid members. While the ordinary coating materials have been described it will be readily understood that gunite or other plastic or cement mixes may be applied in any desired manner. Where the pre-cast monolithic units are used, the necessity for skilled labor is reduced to an absolute minimum while at the same time assuring optimum results both in speed of construction as well as in durability of the finished edifice.

While the improved combination floor and ceiling members have been shown as made of a single piece of metal, the abutting ends of a finished unit being suitably secured as by crimping, as shown at 105 in Fig. 2, it will, of course, be understood that the several arcuate and flat sections and the keyways may be fabricated separately and joined together in any desired manner as by gas or electric welding, brazing, and/or crimping. The resultant structures are mechanically equivalent to those previously described, and permit marked economies in manufacture due to the elimination of costly dies and the annealing steps required in the fabrication of unitary shapes of the type described.

What is claimed is:

1. A ceiling unit of the class described, including an arcuate section of metal, said section having peripheral flanges fixedly associated therewith and reentrant portions disposed longitudinally of said flanges.

2. A ceiling unit of the class described, including a foraminous flat section, a superposed arcuate section, integral peripheral and longitudinal flanges on said arcuate portion, and keyways disposed between said foraminous and arcuate sections, the whole constituting a structural unit.

3. A ceiling unit of the class described, including a single piece of metal, said unit having a foraminous base and a solid arcuate portion above the base, integral keyways dis-

- posed between the solid portion and the foraminous section, and integral angularly disposed ribs on the arcuate section.
4. A combination ceiling and floor unit of the class described, including an arcuate floor supporting section, an integral ceiling section of flat foraminous construction subjacent to said arcuate section, and keyways connecting said sections and adapted to 10 form lateral supports for the assembly.
5. A combination ceiling and floor unit of the class described, including an arcuate floor supporting section, an integral ceiling section of flat foraminous construction subjacent 15 to the arcuate section, and keyways integral with and disposed between the edges of said arcuate and foraminous sections, thereby constituting a unitary self-supporting structure.
- 20 6. An improved ceiling and floor construction, including, in combination a plurality of ceiling and floor units juxtaposed in operative position, said units including integral arcuate floor sections and subjacent foraminous ceiling sections together with integral keyways disposed therebetween; securing members disposed in the keyways of abutting units in locking relationship thereto, and hardenable plastic coatings disposed on the 25 said arcuate and foraminous sections.
7. An improved ceiling and floor construction, including, in combination, a plurality of ceiling and floor units and their associated hardenable plastic coatings; said units 30 including arcuate floor sections, subjacent ceiling sections and intermediate integral keyways forming rigid lateral supports for the units; successive units being so juxtaposed as to abut the respective keyways; ex- 35 pansible key members in said keyways, said keyways being formed at varying heights with respect to the floor units to provide spaces of varying depth in the floor units for the retention of increased amounts of 40 coating material.
8. An improved monolithic floor construction of the class described, including, in combination, a plurality of self-stiffening arcuate floor members, keyways 45 in the floor members in juxtaposition to each other, keys in abutting members whereby to lock them into good mechanical relationship, and a unitary coating of concrete overlying the juxtaposed floor mem- 50 bers.
9. An improved ceiling and floor unit for monolithic structures, including a foraminous base portion, keyways superposed on the edges of the base and integral therewith; and 55 an arcuate floor supporting portion disposed between said keyways and having its bottom edges integral therewith and adjacent said base, said keyways forming rigid lateral supports for the unit.
- 60 65 10. An improved ceiling and floor unit for 110 115 120 125 130
- monolithic structures, including a flat base portion, upwardly extending integral stiffening side members, keyways in said members, and reentrant arcuate top portions integral with the sides and provided with a beam section positioned substantially adjacent said base.
11. An improved monolithic floor construction, including, in combination, a plurality of units as set forth in claim 10, 70 juxtaposed with their keyways in abutting relation, keys in the keyways whereby to lock the units together, and a monolithic filling material disposed on the said units and forming beam sections with intermediate 80 thinner floor sections having metallic support by the stiffening side members of the several units.
12. An improved bridge flooring unit of the type described, including a base portion, 85 vertically disposed stiffening members secured to the sides of the base, keyways intermediate said stiffening members and formed integral therewith, arcuate top portions integral with said stiffening members and 90 with each other, said arcuate portions being provided with reentrant sections and a flat intermediate section adjacent the base to form a beam section of substantial depth.
- In witness whereof I affix my signature. 95
- GUY F. KOTRBATY.
